(57) **CLAIM**

I claim the ornamental design for a pet carrier, as shown and described.

DESCRIPTION

FIG. 1 is the front perspective view of the pet carrier showing my new design,

FIG. 2 is a front view thereof, with the rear view being the mirror image thereof,

FIG. 3 is a left side view thereof,

FIG. 4 is a right side view thereof,

FIG. 5 is a top view thereof; and,

FIG. 6 is a bottom view thereof.

The broken lines depict environmental subject matter, are for illustration only and form no part of the claimed design.
